UNITED STATES PATENT OFFICE

160,904

DISPLAY DEVICE

Lyndall L. Sutherland, Peoria, Ill.

Application May 26, 1950, Serial No. 10,209

Term of patent 7 years

(Cl. D1—2)

To all whom it may concern:

Be it known that I, Lyndall L. Sutherland, a citizen of the United States, residing at Peoria, in the county of Peoria and State of Illinois, have invented a new, original, and ornamental Design for a Display Device, of which the following is a specification, reference being had to the accompanying drawings forming a part thereof.

In the drawings:

Figure 1 is a front elevational view of a display device showing my new design;

Figure 2 is a side elevational view thereof;

Figure 3 is a plan view; and

Figure 4 is a detail sectional view taken substantially on the plane of the line 4—4 of Figure 1.

The dominant features of the design reside in the portions shown in full lines in the drawing.

I claim:

The ornamental design for a display device, as shown and described.

LYNDALL L. SUTHERLAND.
